D10-1. OR D 700 EX

104 P. 700 Design

William B. Lortens' Design for Clocks.

Design for Clock front

Patented May 1, 1855

Des. 700

Wm B. Lorton of the City of New York, etc.
Letters Patent No 700 Dated May 1. 1855

The Schedule referred to in these Letters Patent and
making part of the same

To all whom it may concern.

Be it known, that William
B. Lorton of the City, County and State of New York have
invented a new and useful ornamental Design for the
fronts and sides of Clock cases, and I do hereby declare,
that the following is a full clear and exact description of
the same reference being had to the accompanying drawings
forming part of this specification, in which.

Fig. 1. is a front elevation

Plan No.

Fig. 2. A vertical section or profile through the

Plan No.

Fig. 3. is a horizontal section or profile through
the line x. x in Fig. 1.

Similar letters of reference in each of the several Figs. indicate corresponding parts.

This Design is more particularly adapted for casting in
Cast metal but it is also capable of being manufactured in
plastic material. Its general style is in the Louis Quatorze.
The outline of the casting A, B, cut vertically through the
Centre is similar to that shown by Fig. 2. and the outline
cut through the line x. x similar to that presented by Fig. 3.
The front or panel is flat while the sides which stand off
oblique to the front, take a sweep from the top or upper cornice C, to the base or lower cornice D, in a line somewhat
similar in shape to a cyma recta.

The base or cornice D is ornamented with
mouldings a, b, c, d, e, fig. the first being an inverted
ogee, the second a fillet, the third a bogetus, the fourth
a fillet, the fifth a bead, the sixth a fillet, and the seventh
a bogetus.

The centre of the base, is also embellished with
a leaf ornament E, which is gracefully arranged upon the
mouldings as shown.

The Upper Cornice C is also embellished with
mouldings h, i, f, k, l, which are of a very similar character
to those on the lower cornice.

At the side edges of the front or panel A, there
are two raised scroll ornaments F, G which extend from the
upper cornice C, to the base D, upon which they rest; they
are embellished with leaf ornaments I, J, of the character
represented. There are also two other raised ornaments K.

Des. 700

3

I. S. K. at or near the near edge of the sides B, B. The ornaments H, I, are scrolls and extend from the top of upper cornice C, to the centre of B, where they meet the raised ornaments J, K, and connect with them by oval shaped raised ornaments M, N, which have each a pearl O, in its centre.

The raised ornaments H, I, J, K are embellished with pearl P, P, P, and those J, K, further embellished with leaves Q, Q, Q, Q, of the character shown.

The crown D, which rests upon or is supported by the parts just described, is formed of two scroll ornaments M, M, which form parts of the upper cornice and are connected near the centre of the crown of casting, by a leaf rosette O, which has an egg pumel C, set in it as represented. From each side of this rosette a tendril P, gracefully strikes out and rests upon the upper cornice in the manner illustrated.

The front or panel A, is also embellished nearly all around with slightly raised tracery N, S, T.

The design when made in cast iron may be cast light and thin in all its parts as represented in the sections.

What I claim as my invention and desire to secure by Letters Patent, is.

The design and configuration of the casting represented in the accompanying drawings and herein described forming the front and sides of a clock case.

Witnessed,

S. C. Mallon

J. H. Coombs
